UNITED STATES PATENT OFFICE.

GERARD VANDE, OF LOS ANGELES, CALIFORNIA.

VIBRATOR.

1,173,065.

Specification of Letters Patent.

Patented Feb. 22, 1916.

Application filed March 25, 1914. Serial No. 827,078.

To all whom it may concern:

Be it known that I, GERARD VANDE, a citizen of the United States, residing at Los Angeles, in the county of Los Angeles, State 5 of California, have invented new and useful Improvements in Vibrators, of which the following is a specification.

This invention relates to vibrators of the class described in my application S. N. 10 773,803 filed June 16th, 1913; and the present invention has to do with certain improvements over my vibrator as set forth in said application. In the said application, I describe a vibrator which essentially includes 15 a resilient armature composed of a steel spring and a plurality of soft iron or other laminations, the armature being suspended at each end and the steel spring being continuous and the armature laminations being 20 broken centrally; so that the laminations provide the armature proper to act under the magnetic influence, and the steel spring provides the necessary resiliency for quick action.

25 One of the improvements herein set forth is the provision of means for causing the steel spring to bend through a larger arc than in my prior construction.

Another improvement herein set forth is 30 the matter of mounting of the ends of the armature, to prevent wear and ultimate looseness.

There are several other features of improvement of which I speak in detail hereinafter; reference being had to the accompanying drawings, in which,

Figure 1 is an exterior view of my vibrator, Fig. 2 is a vertical central section of the same, Fig. 3 is a section taken as indicated by line 3—3 of Fig. 2, Fig. 4 is a detail section taken as indicated by line 4—4 of Fig. 2. Fig. 5 is a detail showing the method of mounting the armature ends.

In the drawings, I show my improved 45 form of case at 10, consisting of a thin metal body with two caps 11. The magnet 12 is mounted directly upon the lower cap, this magnet being in the double U-shape with central core 13 and lateral pole pieces 14, as 50 described in my prior application. The winding 15 is preferably paced about the central core; and this central core has a passage 16 through which the brass vibration stem 17 extends. The vibration stem is 55 adapted at 18 at its lower end for the mounting of a massage or other instrument 19; and

at its upper end it connects at 20 with the steel stud 21 which performs the function of connecting the vibration stem 17 with the armature.

The whole armature is composed of a plurality of preferably soft iron laminations 25 which extend from each end of the armature inwardly to a central point, where the laminations are broken as is best shown in Figs. 60 65 2 and 4.

In Fig. 3 the laminations are shown to end on the dotted line 26. The stud 21 projects upwardly between the opposing ends of these laminations, and over the top of the 70 armature there is placed a suitable clip 27, and the stud 21 has a nut 28 adapted to screw down on the clip. A collar 29 on the stud 21 bears upwardly against the lower lamination 25^a, and the nut is screwed down so that 75 the laminations are held loosely between the collar and the clip 27. The inner ends of the laminations are held together by rivets 70. The nut 28 is screwed down to such a position that the laminations are tightly bound 80 between the clip and collar when the armature is bent downwardly to its lower limiting position; i. e. just above the magnet core. In practice this looseness amounts to about one sixty-fourth of an inch. This lower 85 lamination 25^a, and also the uppermost lamination 25^b, is preferably of steel, for the purpose of resisting wear; the intermediate laminations being preferably of soft iron. Immediately below the lower lamination 25^a 90 there are short laminations 25^c which do not extend inwardly as far as the laminations 25, ending as is clearly shown in Figs. 2 and 3 at a point somewhat distant from the center of the armature. Beneath these 95 laminations 25^c there are placed the two steel springs 30 which give resiliency to the armature. The collar 29 which bears upwardly against the lower lamination 25^a is flattened at each side as shown at 29^a in Fig. 3, and is 100 confined laterally between the springs 30 so that it is thereby prevented from turning.

The whole armature construction is held together at the ends by suitable clips 40 and rivets 41. These clips 40 extend down on 105 each side of the armature and are pivotally connected at 42 with links 43 which are pivoted at 44 to the pole pieces 14 of the magnet. The upper ends of the pole pieces 14 are beveled as shown at 14^a, so that the ends 110 of the armature rest at or near the points designated 45. The pivots 42 are placed

close to the points of bearing 45, so that the pivotal movement on the points of bearing will coincide with the pivotal movement around the pivots 42. The links 43 accommodate any movement other than pivotal of the ends of the armature.

In practical use, the armature, in its central up and down movement, merely moves on the points 45 as pivotal points. There is no, or very little, sliding movement; and the movement as a whole is such that there is very little wear and very little tendency to looseness of the parts. Whereas an ordinary pivot at the ends of the armature would soon wear loose, this link supported pivot has very little tendency to wear loose, as has been fully and amply demonstrated by long continuous operation of my device. The magnet 15 is supplied with alternating current of the ordinary sort or with any intermittent current through a suitable cord 50, and the intermittent magnetism of the magnet will attract the armature, throwing it into rapid vibration. The springs 30 act on the armature to throw it back to and above the position shown in Fig. 2 from a lower position to which it has been attracted by the magnet. The spring acts on the armature proper through the medium of the short laminations 25. The distance between the ends of these laminations being considerable, the spring is allowed to bend through an arc of corresponding length. In this manner, short bending of the spring is entirely eradicated; and I have found that the spring will practically last indefinitely under ordinary conditions of use.

To control the amplitude of armature vibration, I provide a suitable adjustable stop. This stop comprises an adjusting screw 60 having on its upper end a thumb nut 61 and carrying at its lower end a rubber buffer 62. The rubber buffer is mounted in a ferrule or collar 63 on the under side of a nut 64 which is permanently mounted upon the lower end of the screw 60, turning with the screw. The screw works in a nut 65 secured to the under side of the upper cap 11; and with the nut there is also secured a spring detent 66 extending downwardly and pressing against the nut 64. This spring detent has a notch or slot 67, as shown in Fig. 3, and in which the corners of the nut 64 are caught, while the flat sides of the nut are engaged by the spring detent 66 as a whole. These engagements of the spring detent with the nut serve to hold the adjusting screw 60 and the buffer 62 in any set position. To lengthen the vibration of the armature it is only necessary to screw the thumb nut 61 upwardly; to shorten the vibration the thumb nut 61 is screwed downwardly.

I claim—

1. A vibrator, comprising a double-U-shaped magnet with a central core and lat-

eral pole extensions, an energizing coil for the magnet and a spring armature attached to both polar extensions and extending medially over the core, the ends of the armature pivotally resting on the lateral pole extensions, and means for holding each armature end down on the pole pieces including a clip attached to the armature end, a link pivoted to the pole piece, and pivotal connection between the clip and link approximately co-axial with the pivotal bearing of the armature on the pole piece.

2. A vibrator, comprising a double-U-shaped magnet with a central core and lateral pole extensions on opposite sides thereof, an energizing coil for the core, and a spring armature pivotally attached to both polar extensions and extending medially over the core, the ends of the armature pivotally resting on the lateral pole extensions, and means for holding each armature end down on the pole pieces including a clip attached to the armature end, a link pivoted to the pole piece, and pivotal connection between the clip and link approximately co-axial with the pivotal bearing of the armature on the pole piece.

3. A vibrator, comprising a double-U-shaped magnet with a central core and lateral pole extensions on opposite sides thereof, an energizing coil for the core, and a spring armature attached to both polar extensions and extending medially over the core, said armature comprising a body of soft iron lamina and a flat strip of spring steel, the ends of the armature pivotally resting on the lateral pole extensions, and means for holding each armature end down on the pole pieces including a clip attached to the armature end, a link pivoted to the pole piece, and pivotal connection between the clip and link approximately co-axial with the pivotal bearing of the armature on the pole piece.

4. A vibrator, comprising a double-U-shaped magnet with a central core and lateral pole extensions, an energizing coil for the magnet, an armature connected to both polar extensions and extending medially over the core, and spring means for rendering resilient the motion of the armature to and from the central core, the ends of the armature pivotally resting on the lateral pole extensions, and means for holding each armature end down on the pole pieces including a clip attached to the armature end, a link pivoted to the pole piece, and pivotal connection between the clip and link approximately co-axial with the pivotal bearing of the armature on the pole piece.

5. In a device of the class described, a spring armature supported by mountings at each end and medially free to vibrate, said mountings for the armature ends including supporting members upon which the arma-

ture ends pivotally rest, and links pivotally connected to said supporting members and pivotally connected with the armature ends at points approximately co-axial with the 5 pivotal bearings of the armature ends on said members.

6. In a device of the class described, a spring armature supported by mountings at each end and medially free to vibrate, said 10 armature embodying an elongate body broken medially and a flat strip of spring metal continuous from end to end of the armature, the body being secured to the flat spring, said mountings for the armature 15 embodying supporting members upon which the armature ends pivotally rest, clips attached to the armature ends, and links pivotally connected to said supporting members and pivotally connected to said clips at 20 points approximately co-axial with the pivotal bearings of the armature ends on said members.

7. A vibrator, comprising a double U-shaped magnet with a central core and lateral pole extensions on opposite sides thereof, an energizing coil for the core, a spring armature attached to both polar extensions and extending medially over the core, said armature comprising an elongate body 30 broken centrally over the core and a flat spring continuous between the points of attachment to the lateral pole extensions, the body contacting near the ends with the spring but not at its center, and an applicator stem connected with the body at its center and not connected with the spring.

8. An armature construction for a vibrator of the character described, embodying a spring strip continuous from end to end of 40 the armature, an elongate body broken centrally and affixed to the spring strip at its ends, mountings for the ends of the armature leaving the center free to vibrate, a stem passing transversely through the break 45 in the armature body, and a pair of members affixed to the stem one on each side of the armature body, said members loosely engaging the armature body on each side of the central break.

50 9. An armature construction for a vibrator of the character described, embodying a spring strip continuous from end to end of the armature, an elongate body broken centrally and affixed to the spring strip at its 55 ends, mountings for the ends of the armature leaving the center free to vibrate, a stem passing transversely through the break in the armature body, and a pair of members affixed to the stem one on each side of 60 the armature body, said members engaging the armature body on each side of the central break and being adjustable on the stem

so that the looseness of engagement with the armature body may be varied.

10. A vibrator, comprising a double U-shaped magnet with a central core and lateral pole extensions on opposite sides thereof, an energizing coil for the core, a spring armature attached terminally to both polar extensions and extending medially over the 70 core, said armature comprising an elongate body broken centrally over the core and a flat steel spring continuous between the points of attachment to the lateral pole extensions, the body contacting with the spring 75 near its end but not in its medial portions, an applicator stem passing transversely through the break in the armature body, and a pair of members affixed to the stem one on each side of the armature body, said members holding the body loosely between them but not holding the flat spring between them, 80 said members engaging the armature body on each side of the central break and being adjustable on the stem so that the looseness 85 of engagement with the armature body may be varied.

11. In a vibrator, a vibrating armature supported at each end and medially free to vibrate, said armature including a body of 90 magnetic material broken medially, a stem passing transversely through the break in the body, and a pair of members on said stem one on each side of the armature body, said members extending on each side of the stem 95 and on each side of the break so as to engage the body on each side of the break, and said members loosely engaging the body when in its normal unstressed position.

12. In a vibrator, a magnet with an energizing coil, a vibrating armature supported at each end and medially free to vibrate over the magnet, said armature including a body of magnetic material broken medially, a stem passing transversely through the break 100 in the body, a clip on the stem above the body engaging the upper surface of the body a considerable distance on each side of the break therein, a collar on the stem below the body engaging the under surface of the body 110 on each side of the break therein, the collar and clip loosely holding the body between them, and means for adjusting the distance between the clip and collar to adjust the looseness of their engagement with the armature body.

In witness that I claim the foregoing I have hereunto subscribed my name this 18th day of March, 1914.

G. VANDE.
